DESIGN FOR A COMBINED LAMP AND
FLOWER POT

Mariano Reres, Brooklyn, N. Y.

Application December 20, 1946, Serial No. 135,636

Term of patent 7 years

(Cl. D48—20)

To all whom it may concern:

Be it known that Mariano Reres, a citizen of the United States of America, residing at Brooklyn, New York, in the county of Kings and State of New York, has invented a new, original, and ornamental Design for a Combined Lamp and Flower Pot, of which the following is a specification, reference being had to the accompanying drawing, forming part thereof.

Figure 1 is a side view of the combined lamp and flower pot, embodying my new design.

Figure 2 is a plan view taken on line 2—2 of Fig. 1.

Figure 3 is a cross sectional view taken on line 3—3 of Fig. 2.

The characteristic features of my design reside in the portions shown in full lines.

I claim:

The ornamental design for a combined lamp and flower pot, as shown and described.

MARIANO RERES.
